Des. 184,971
Patented Apr. 21, 1959

184,971

TELEVISION ANTENNA

Thomas Vitanza, Buffalo, N.Y.

Application May 5, 1958, Serial No. 50,765

Term of patent 14 years

(Cl. D26—14)

Fig. 1.

Fig. 2.

Fig. 3.

Fig. 1 is a front elevational view of a television antenna, showing my new design.

Fig. 2 is a top plan view thereof.

Fig. 3 is a right side view thereof.

Fig. 4 is a perspective view thereof.

I claim:

The ornamental design for a television antenna, as shown.
